DESIGN FOR A STAPLING MACHINE

Herbert Chandler Ide, Arlington, Va.

Application October 31, 1946, Serial No. 134,401

Term of patent 14 years

(Cl. D74—1)

To all whom it may concern:

Be it known that I, Herbert Chandler Ide, a citizen of the United States, residing at Arlington, in the county of Arlington and State of Virginia, have invented a new, original, and ornamental Design for a Stapling Machine, of which the following is a specification, reference being had to the accompanying drawing, forming part thereof.

Figure 1 is a front perspective view of a stapling machine, showing my new design;

Figure 2 is a side elevational view thereof; and

Figure 3 is a plan view of the same.

The essential features of my design reside in the portions shown in full lines.

I claim:

The ornamental design for a stapling machine, as shown and described.

HERBERT CHANDLER IDE.
